(57) **CLAIM**

The ornamental design of apparatus for sleep information detection as shown and described.

DESCRIPTION

FIG. 1 is a top, rear and left side perspective view of a first embodiment of the apparatus for sleep information detection showing our new design.

FIG. 2 is a rear side view of the first embodiment of the apparatus for sleep information detection;

FIG. 3 is a front side view of the first embodiment of the apparatus for sleep information detection;

FIG. 4 is a right-side view of the first embodiment of the apparatus for sleep information detection;

FIG. 5 is a left-side view of the first embodiment of the apparatus for sleep information detection;

FIG. 6 is a top view of the first embodiment of the apparatus for sleep information detection;

FIG. 7 is a bottom view of the first embodiment of the apparatus for sleep information detection; and,

FIG. 8 is a top view of the first embodiment of the apparatus for sleep information detection in a facial detection environment.
